UNITED STATES PATENT OFFICE.

ALFRED M. LOFLAND, OF LEBANON, INDIANA, ASSIGNOR OF ONE-HALF TO LEWIS C. WILLIS, OF INDIANAPOLIS, INDIANA.

METAL WHEEL.

1,412,123.

Specification of Letters Patent. Patented Apr. 11, 1922.

Application filed January 20, 1921. Serial No. 438,692.

To all whom it may concern:

Be it known that I, ALFRED M. LOFLAND, a citizen of the United States, residing at Lebanon, in the county of Boone and State 5 of Indiana, have invented certain new and useful Improvements in Metal Wheels, of which the following is a full, clear, and exact description.

The invention which constitutes the subject matter of this application relates to 10 improvements in the construction and manufacture of disk wheels.

Among the principal objects of the invention are first, to cheapen the cost of manufacture of bracing centers by manufacturing them of waste or inexpensive material; second, to reduce materially the weight of the same; and third, to give increased strength thereto, at least to insure a maximum 20 strength with the minimum of weight. Broadly speaking therefore the invention comprises a center bracing for metal disk wheels which is made up of a plurality of stamped metal sections secured to each other 25 and adapted to surround the hub of the wheel, each of said sections being provided with portions extending preferably in a radial direction towards the periphery of the wheel. In the preferred embodiment 30 of the invention all of the sections are curved or bent, thereby materially increasing their strength. The invention further consists of the combination of a metal wheel, of a double disk type with a center bracing 35 such as referred to above.

Other objects, advantages and features will more clearly appear from the detailed description below taken in connection with the accompanying drawings in which:—

40 Figure 1 is a side view of a metal wheel particularly adapted for the front of a truck, with parts broken away to illustrate my novel form of center bracing or spider applied thereto, the view being in the direction 45 of the axis of rotation of the wheel.

Fig. 2 is a central sectional view of the metal wheel illustrated in Figure 1 with my improvements embodied therein;

Fig. 3 is a perspective view of one of a 50 plurality of sections, preferably made of sheet metal, that go to make up the center bracing shown in Figures 1 and 2;

Figs. 4, 5, 6 and 7 illustrate a slightly modified form of wheel and bracing center

and particularly adapted for the rear wheel 55 of a truck where additional bracing effect is required.

Referring to the drawings in detail, and first with particular reference to the form of the invention illustrated in Figs. 1 to 3, the numerals 10 and 11 designate respectively 60 the inner and outer disks of what is commonly known as a double disk metal wheel. In the form shown the disks radiate a substantial distance from the hub as indicated 65 at 12 and 13 and then one or both converge sufficiently to enable them to meet in a plane where they are riveted or otherwise rigidly secured to each other, the converging portions being indicated at 14 and 15 and the 70 meeting plane being indicated at 16. The peripheries of the disks are turned at right angles to the meeting plane, as indicated at 17 and 18, to enable the rim or felloe 19 to be secured thereto in any well known man- 75 ner.

Between the portions of the disk 12 and 13, which are preferably parallel to each other, is located the improved built-up bracing center, as more clearly illustrated in 80 Figures 1 and 3. This center comprises a plurality of stamped or drawn irregular sections of sheet metal having the portions 20 which are preferably struck up in the form shown, as nearly as possible on the arc 85 of a circle to give it maximum strength, and the portions 21 which preferably extend outwardly in a radial direction and which are preferably provided with ends 22. The end 90 of each portion 20 adjacent to the portion 21 is riveted, spot welded or otherwise secured on the outside of and to the opposite end of the succeeding portion 20 and when so secured to each other presents a unitary structure of substantially circular formation and 95 built of sheet metal or wrought steel. The portions 22 may be made straight with sections 21, but are preferably curved as this adds materially to the strength of the bracing center as a whole and in particular 100 prevents the outwardly extending portions from any tendency to collapse.

The hub of the wheel is diagrammatically illustrated at 23 and is provided with the radiating flanges 24 and 25 which overlap 105 the exterior of the disks 10 and 11 respectively. The disks 10 and 11 are provided with perforations 26 and 27 respectively and

the flanges 24 and 25 with perforations 28 and 29 to receive bolts 30 for rigidly and securely clamping the disks to the hub flanges. In assembling, the radiating portions 21—22 of the sections are preferably located adjacent the perforations so that the thrust due to the tightening of the bolts passing through said holes will bear as nearly as possible directly upon said sections, thereby avoiding the distortion of the metal which might otherwise occur where the disks are made up of light material and where a built-up center is employed of only a few sections. I find that the best results are accomplished in locating one annular series of bolts within the curved portions 22. In Figs. 1 and 2 of the drawing I have illustrated only one annular series of such bolts, but it will be seen from Figs. 4 and 5 that a plurality of series may be employed depending upon a number of factors, and chiefly the duty required of the particular wheel. The wheel illustrated in Figs. 1 to 3 of the drawings is designed for the front of a truck, but it is well understood that the duty of the rear wheel for the same truck is materially greater and therefore should be and is built stronger, as by increasing the length of the radiating portions 21 and by adding one or more additional series of securing bolts.

The width of each of the sections 20, 21 and 22 in any particular wheel is the same and they are so united that the corresponding edges on either side lie in a single plane so that when the spider is positioned between the parallel portions 12 and 14 of the disks 10 and 11, all portions of said edges will contact with said disks. The improved bracing center described above not only results in a wheel that is lighter and less expensive to manufacture, but it possesses additional strength and wearing qualities.

As previously stated, Figs. 4 to 7 inclusive illustrate a modified form of wheel and wheel center, the important difference between it and the form shown in Figs. 1 to 3 being as follows. On the arcuate portions 20 of any or all of the sections is riveted, spot welded or otherwise secured thereto, radiating portions 31. All of the radiating portions extend outwardly to a greater distance thereby giving the disks a bracing effect for a greater circumferential extent. And as previously stated a plurality of series of bolts 30 is employed in securing the hub-flanges to the disks.

It will be understood that I do not limit myself to the exact construction shown and described as many changes can be made in points of detail and other embodiments resorted to without deviating from the true spirit and scope of my invention, as defined by the appended claims.

What I claim is:

1. A center for bracing disk wheels com-

prising a plurality of metal sections, each of said sections having an arcuate and a radial portion, the arcuate portions of the sections being united to each other in succession in a circumferential direction to form a circular construction adapted to surround the hub of the wheel.

2. A center for bracing disk wheels comprising a plurality of metal sections having arcuate portions united to each other in succession in a circumferential direction to form a circular construction adapted to surround the hub of the wheel and having portions extending radially therefrom towards the periphery of the wheel.

3. A center for bracing disk wheels comprising a plurality of metal sections having arcuate portions united to each other to form a circular construction adapted to surround the hub of the wheel and having portions extending outwardly therefrom towards the periphery of the wheel, the ends of the said last mentioned portions being curved not only to add strength to said portions but to give more bracing effect to the disks of the wheel.

4. A center for bracing double disk wheels comprising a plurality of metal sections having overlapping arcuate portions united to each other at the overlaps in succession in a circumferential direction to form a substantially circular construction adapted to surround the hub of the wheel and having portions extending outwardly therefrom towards the periphery of the wheel.

5. A center for bracing double disk wheels comprising a plurality of sections each of which is stamped up from a single piece of metal and all of them having arcuate portions united to each other in succession in a circumferential direction to form a circular construction adapted to surround the hub of the wheel and each section having an integral portion extending radially with respect to the axis of the hub.

6. A center for bracing double disk wheels comprising a plurality of sections each stamped up from a single piece of metal and all of them having arcuate portions united to each other to form a circular construction adapted to surround the hub of the wheel and each section having an integral portion extending radially with respect to the axis of the wheel hub with the extreme end of said integral portion curved or bent to give the same increased strength.

7. A center for bracing double disk wheels comprising a plurality of stamped metal sections secured to each other in succession in a circumferential direction and adapted to surround the hub of the wheel, each of said sections being provided with portions extending radially therefrom towards the periphery of the wheel.

- comprising a plurality of stamped metal sections secured to each other and adapted to surround the hub of the wheel, each of said sections being provided with portions integral with and extending radially therefrom towards the periphery of the wheel, the outer ends of said portions being curved to give increased strength to the same.
9. A center for bracing double disk wheels comprising a plurality of unitary metallic sections having arcuate portions to form a circular construction adapted to surround the hub of the wheel, one end of each of said arcuate portions overlapping and secured to the adjacent end of the next succeeding section, and a second portion integral with and extending outwardly from the overlapping end of the arcuate portion.
10. In a wheel, a flanged hub and a pair of sheet metal disks extending outwardly from the hub, in combination with a bracing center interposed between said disks comprising a plurality of stamped metallic sections secured to each other in succession in a circumferential direction and surrounding said hub, each of said sections being provided with portions extending radially therefrom, and means passing through the flanges of said hub and through the disks in close proximity to said portions for securing the hub to said disks.
11. A center for bracing double disk wheels comprising a plurality of unitary metallic sections having portions united to form a construction adapted to surround the hub of the wheel, one end of each of said portions overlapping and secured to the adjacent end of the next succeeding section, and a second portion integral with and extending from the overlapping end of the first mentioned portion.
12. In a wheel, a flanged hub and a pair of sheet metal disks extending outwardly from the hub, in combination with a center bracing interposed between said disks comprising a plurality of stamped metallic sections secured to each other in succession in a circumferential direction and surrounding said hub, and means passing through the flanges of said hub and through the disks in close proximity to said portions for securing the hub to said disks.
13. A center for bracing disk wheels comprising a plurality of irregularly shaped metal sections secured to each other in succession in a circumferential direction and adapted to surround the hub of the wheel.
14. A center for bracing double disk wheels comprising a plurality of metal sections having arcuate portions united to each other in succession in a circumferential direction to form a circular construction adapted to surround the hub of the wheel and having portions extending radially therefrom towards the periphery of the wheel, the flat surfaces of said portions being arranged parallel to the axis of the wheel.
15. A center for bracing double disk wheels comprising a plurality of metal sections having overlapping arcuate portions the flat surfaces of which are parallel to the axis of the wheel, said portions united to each other at the overlaps in succession in a circumferential direction to form a substantially circular construction adapted to surround the hub of the wheel and having portions extending outwardly therefrom towards the periphery of the wheel.
16. A center for bracing double disk wheels comprising a plurality of sections the flat surfaces of which are parallel to the axis of the wheel, each of said sections being stamped up from a single piece of metal and all of them having arcuate portions united to each other in succession in a circumferential direction to form a circular construction adapted to surround the hub of the wheel and each section having an integral portion extending radially with respect to the axis of the hub.
17. A center for bracing double disk wheels comprising a plurality of stamped metal sections, the flat surfaces of which are parallel to the axis of the wheel, said sections being secured to each other in succession in a circumferential direction and adapted to surround the hub of the wheel, and each of said sections being provided with portions extending radially therefrom towards the periphery of the wheel.
18. In a wheel, a flanged hub and a pair of sheet metal disks extending outwardly from the hub, in combination with a bracing center interposed between said disks comprising a plurality of stamped metallic sections the flat surfaces of which are parallel to the axis of the wheel, said sections being secured to each other in succession in a circumferential direction and surrounding said hub, each of said sections being provided with portions extending radially therefrom, and means passing through the flanges of said hub and through the disks in close proximity to said portions for securing the hub to said disks.
19. A center for bracing double disk wheels comprising a plurality of irregularly shaped metal sections, the flat surfaces of which are parallel to the axis of the wheel, said sections being secured to each other in succession in a circumferential direction and adapted to surround the hub of the wheel.
20. A center for bracing double disk wheels comprising a plurality of irregularly shaped stamped metal sections secured to each other in succession in a circumferential direction to form a substantially circular construction adapted to surround the hub of the wheel.
21. In a wheel, a flanged hub, and a pair

of sheet metal disks extending outwardly from said hub, in combination with a bracing center interposed between said disks comprising a plurality of metallic sections having portions thereof united to each other to form a built-up construction adapted to surround the hub of the wheel and having portions extending radially therefrom towards the periphery of the wheel, the flat surfaces of said portions being arranged parallel to the axis of the wheel with the corresponding edges on either side located in planes at substantially right angles to the axis of the wheel and in contact with said disks, and means passing through said disks in proximity to said sections for rigidly securing said disks in contact with said edges.

22. In a wheel, a flanged hub, and a pair of sheet metal disks spaced from each other and extending outwardly from and for a substantial distance at right angles to said hub, in combination with a bracing center

interposed between said disks comprising a plurality of irregularly shaped stamped metallic sections having arcuate portions united to each other to form a built-up construction adapted to surround the hub of the wheel and having portions extending radially therefrom towards the periphery of the wheel, the flat surfaces of said portions being arranged parallel to the axis of the wheel with the corresponding edges on either side located in planes at substantially right angles to the axis of the wheel and in contact with those portions of said disks which are arranged at right angles to the hub, and means passing through said disks in proximity to said sections for rigidly securing said disks in contact with said edges.

In testimony whereof, I have hereunto set my hand and affixed my seal this 15th day of January 1921.

ALFRED M. LOFLAND.
